ROBERT C. COLE, OF HARTFORD, CONNECTICUT, ASSIGNEE TO THE JOHNS-PRATT COMPANY, OF HARTFORD, CONNECTICUT, A CORPORATION OF CONNECTICUT.

CARTRIDGE-FUSE.

1,309,508.

Specification of Letters Patent.

Patented July 8, 1919.

Application filed January 21, 1919. Serial No. 272,824.

To all whom it may concern:

Be it known that I, ROBERT C. COLE, a citizen of the United States, residing at Hartford, in the county of Hartford and 5 State of Connecticut, have invented a new and useful Improvement in Cartridge-Fuses, of which the following is a specification.

This invention relates to the construction of those inclosed electric safety fuses of the 10 cartridge type which are more particularly designed for the protection of delicate apparatus, such as multiple motor controls, using small currents, for example, 1 to 3 amperes, that are connected with light and 15 power circuits of common commercial pressures, for instance 250 and 600 volts. Owing to the small capacity of such fuses the fusible link is very delicate, that, for illustration, of a 600 volt, 1 ampere fuse, if of zinc 20 wire would be approximately 2.5 inches long and .0028 of an inch in diameter. These fuses must be accurately calibrated and must be durable, and the allowable interval between safe load and blow must be small, 25 otherwise either they would not perform their functions as safety devices or they would open prematurely and cause great annoyance. Very slight variations in dimension, construction, and arrangement of 30 the elements effect greater proportional changes in the carrying capacity and blowing time of these small fuses than in fuses of larger capacity. Furthermore, these devices must be capable of being manufactured 35 in considerable quantities at a reasonable cost.

It has been customary to solder the ends of the fusible links to the terminals and connect these terminals with conducting caps 40 on the ends of a tubular insulating case and to fill the case with a granular compound designed to absorb and condense the gases and flash incident to the blowing of the fuse. Soldering such joints necessitates the use of 45 flux. Heat of the solder frequently melts the ends of these delicate links, and the flux if not entirely removed causes a local battery action at the joints after the case has been filled. Under these conditions the links 50 are sooner or later rendered entirely ineffective or their carrying capacity is altered so that the fuses are not uniform and reliable. In fact, in the construction previously employed, a high percentage of these 55 small fuses are rendered ineffective as a re-

sult of soldering the links to the terminals, even with the exercise of care in their manufacture. Moreover, in the prior structures it is difficult to handle without breaking, and keep straight and in the center of the case, 60 such very delicate fuse links, and their condition in this respect affects the load and blowing interval.

The object of this invention is to provide a construction for such small capacity fuses 65 which renders soldering of the delicate links to the terminals unnecessary, thus eliminating the danger of melting the links or subsequent deterioration from galvanic action, and which permits the fuse links to be 70 handled rapidly and quickly assembled in large quantities, straight and in the center of the case, thus insuring accurate and reliable fuses of small capacity at minimum cost.

Figure 1 of the accompanying drawings 75 shows a central longitudinal section of a fuse constructed according to this invention. Fig. 2 is a view looking at one end with the metal end cap removed from the insulating 80 case. Fig. 3 is a view of the insulating strut upon which is mounted the delicate fusible link.

The tubular case 1 is made of insulating material and provided with metal end caps 2 in 85 the usual manner. Loosely located in the case and extending longitudinally thereof is a strip of insulating material 3 that has projections or feet 4 which extend diametrically across the case some distance apart. 90 This piece which may be termed a "strut" is desirably punched or cut to shape from stiff paper, fiber or the like sheet insulating material. The fine fusible link 5, ordinarily round zinc wire, is mounted on this strut. 95 The feet 4 of the strut are preferably notched and the ends of the link 5 are wrapped about the notched sections, after which the inner ends of the terminal wires 6, ordinarily soft copper wire, are wrapped about the notched 100 sections of the strut feet, over the wound ends of the fusible link.

The insulating strut is made slightly shorter than the length of the case and a little less in width than the inner diameter of 105 the case, and the notches in the feet are so positioned that the link and terminal wires will extend substantially in the longitudinal axis of the case when the parts are assembled. The terminal wires extend through 110

perforations in the end caps and their outer ends are connected therewith in the usual way, preferably by solder. Before the second end cap is placed in position, the case 5 may be filled with the granular material 7 commonly used for absorbing and condensing the gases and flame resulting from the blowing of the fuse.

This construction enables uniformly accurate and reliable small capacity fuses having 10 very delicate fusible links to be manufactured in large quantities, rapidly, and expensively without the exercise of extreme care.

15 The invention claimed is:

1. A cartridge fuse having an insulating case, metal caps at the ends of the case, a piece of sheet insulation loosely located in the case and extending longitudinally and 20 transversely thereof, a fusible wire extending between and having its ends wrapped about portions of said piece of insulation, and terminal wires with their inner ends wrapped about the inner ends of the fusible 25 wire and their outer ends electrically connected with the end caps.

2. A cartridge fuse having an insulating case, metal caps at the ends of the case, an 30 insulating strip with projecting portions loosely located in the case, a fusible wire stretched between and having its ends

wrapped about the projecting portions of the insulating strip, and terminal wires with their inner ends wrapped about the projecting portions of the insulating strip and inner 35 ends of the fusible wire and with their outer ends electrically connected with the end caps.

3. A cartridge fuse having an insulating case, metal caps at the ends of the case, a strip of sheet insulation extending longitudinally in the interior of the case with 40 projections therefrom extending diametrically across the interior of the case, said projections having notches in their edges in line with the axis of the case, a fusible wire 45 with its ends wrapped about the notched sections of said insulating piece, and terminal wires with their inner ends wrapped about the ends of said fusible wire and with 50 their outer ends electrically connected with the end caps.

4. An element for a cartridge fuse comprising a strip of sheet insulation with portions projecting therefrom, a fusible wire 55 stretched between and having its ends wrapped about the projecting portions of the insulating strip, and terminal wires with ends wrapped about the projecting portions of the insulating strip and ends of the fusible wire. 60

ROBERT C. COLE.
